US00D887269S

(12) **United States Design Patent** (10) **Patent No.:** **US D887,269 S**
(45) **Date of Patent:** **** Jun. 16, 2020**

(54) **SPOUT FOR A CONTAINER**

(71) Applicant: **B.R. Tenant, Inc.**, Des Plaines, IL (US)

(72) Inventor: **Barbara Marik**, Des Plaines, IL (US)

(**) Term: **15 Years**

(21) Appl. No.: **29/668,680**

(22) Filed: **Nov. 1, 2018**

(51) LOC (12) Cl. **09-07**

(52) U.S. Cl.

USPC **D9/453; D9/447**

CLAIM

The ornamental design for the spout for a container, as shown and described.

DESCRIPTION

FIG. 1 is a perspective view of a spout for a container showing my new design;

FIG. 2 is another perspective view thereof;

FIG. 3 is a side view thereof, with other side views being substantially similar;

FIG. 4 is a top view thereof; and,

FIG. 5 is a bottom view thereof.

The broken lines are shown for the purpose of illustrating parts of the article that form no part of the claim.

1 Claim, 2 Drawing Sheets
